CLAIM

The ornamental design for an adjustable tiki lantern arm, substantially as shown and described.

DESCRIPTION

FIG. 1 is a perspective view of the adjustable tiki lantern arm embodying my new design and shown attached to a rail.

FIG. 2 is a front view of the adjustable tiki lantern arm shown in FIG. 1.

FIG. 3 is a left side view of the adjustable tiki lantern arm shown in FIG. 1.

FIG. 4 is a rear view of the adjustable tiki lantern arm shown in FIG. 1.

FIG. 5 is a right side view of the adjustable tiki lantern arm shown in FIG. 1.

FIG. 6 is a top view of the adjustable tiki lantern arm shown in FIG. 1; and,

FIG. 7 is a bottom view of the adjustable tiki lantern arm shown in FIG. 1.

The broken lines shown on the drawings are for illustrative purposes only and form no part of the claimed design.
